LOUIS F. RENAULT AND CHRISTIE J. DRAGO, OF NEW YORK, N. Y.

CLOTHES-LINE SUPPORT.

1,165,125.

Specification of Letters Patent. Patented Dec. 21, 1915.

Application filed October 26, 1915. Serial No. 57,948.

To all whom it may concern:

Be it known that we, LOUIS F. RENAULT and CHRISTIE J. DRAGO, citizens of the United States, and residents of the city of New York, borough of Brooklyn, in the county of Kings and State of New York, have invented a new and Improved Clothes-Line Support, of which the following is a full, clear, and exact description.

This invention relates to clothes line supports and has particular reference to that class of such devices as are intended for use in apartment houses or the like where the clothes to be dried are hung from windows along lines leading to distant posts or other supports.

Among the objects of the invention is to provide a means of a cheap, simple and reliable nature adapting the operator to hang the clothes upon the line without the necessity of reaching out of the window for this purpose.

It is well known that in large cities where the clothes are hung from upstairs windows, many accidents and fatalities result from the reaching or hanging out of the windows, and hence may attempts have been made to provide a suitable apparatus to support the adjacent end of a clothes line to obviate such dangerous operation.

With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference characters designate the same parts in the several views, and in which—

Figure 1 is a side elevation of a clothes line apparatus showing the position thereof with respect to the building while the clothes are being put upon the line and projected outwardly through the window; Fig. 2 is a similar view showing the relative positions of the parts when the clothes are in drying position and the window closed; Fig. 3 is an enlarged side elevation of the main parts of the structure indicating the position of the supporting arm when projected within the building; Fig. 4 is a plan view, parts being in section on the line 4—4 of Fig. 3; Fig. 5 is a vertical edge view of the main bracket as will be seen from the line 5—5 of

Fig. 3 and indicating the arm in section; Fig. 6 is a perspective view of the said bracket; and Fig. 7 is a vertical sectional detail on the line 7—7 of Fig. 3.

Referring now more particularly to the drawings we show a main bracket 10 of symmetrical form and hence adapted to secure to either the right or left side of a window frame, depending upon the position of the distant support 11 or the individual preference of the operator. This bracket comprises the main web portion 12 approximately of circular form and provided with a forwardly projecting circular flange 13. The web and flange members are formed integral with each other and with an angle piece comprising a plate 14 lying in substantially the same plane as the web 12 and a right-angularly disposed plate 15. This bracket is designed to be secured rigidly but removably to the window frame 16 through the angle piece plates. The means we prefer to use for this purpose includes a metal plate 17 adapted to be secured as by means of wood screws 18 to that edge or face of the window frame adjacent the window opening. The plate or bar 17 is thus secured in vertical position and in a plane perpendicular to the plane of the window. This plate or bar 17 may be of any suitable size or length but of sufficient strength to make a rigid base for the bracket. One of these plates or bars may be placed on each side of the window so as to accommodate the attachment for either side with a minimum amount of trouble. In addition to the holes for the wood screws 18, the bar 17 is tapped at a plurality of places, as shown at 19, for machine screws 20 which pass through holes in the ears 21 at the upper and lower ends of the plate 14 and whereby the plate 14 is clamped rigidly to the bar 17, this connection constituting the main supporting means for the bracket on the window frame.

The plate 15 is provided with a hole 22 through which a lag screw 23 projects at right angles to the screws 18 and 20. The lag screw is provided at its outer end with a movable head 24 whereby, after the lag screw is once set in position, the plate 15 may be attached to or detached from the screw. This may be regarded as a temporary holder for the bracket preliminary to inserting the machine screws 20 as a permanent fastener.

At the center of the web or disk 12 is pro-

vided a boss 25 having an axial hole 26 therethrough. The outer surface of the boss is approximately cylindrical but preferably slightly tapered. The length of this boss 5 is slightly less than the width of the flange 12. A pivot pin or bolt 27 is fitted through the hole 26 and projects a considerable distance from the front end of the boss. This pin may be threaded into the boss and upset 10 at its rear end so as to become a fixture therein, as shown at 28.

At 29 is indicated an arm shown as made of tubular material and extending directly 15 diametrically through the middle portion of a sleeve 30 fitted at its rear end upon the boss 25. The arm is bored at 31 at the axis of the sleeve to receive the pin 27. It follows, therefore, that the arm is held rigidly 20 from rotation in the sleeve, and when the sleeve is fitted upon the boss 25 it is immovable with respect to the arm. The sleeve 25 is of ample size and strength for its purpose, and even though the pin 27 is passed through the arm, the reinforcement of the arm resulting from the sleeve embracing it provides ample strength for the arm. A hand wheel or nut 32 having a tapered boss 33 is tapped upon the front or free end of the pin 27. The boss 33 fits into the front 30 end of the sleeve 30, and upon the tightening of the nut 32 the arm and sleeve are locked in definite position with respect to the bracket 10. The arm 29 is made of suitable length to reach well into the building 35 from the outside of the window frame and coöperates at points 34 and 35 with the flange 13 on diametrically opposite sides of the axis of the pin 27. The bracket is mounted upon the window frame as closely 40 adjacent the bottom of the upper sash as convenient, and for ordinary purposes the arm 29 is locked in horizontal position for hanging the clothes upon the line. At such time the arm at the points 34 and 35 will 45 rest in notches 36 and 37, but to accommodate the height of the arm to taller or shorter persons, other pairs of notches 38 and 39 are provided on said flange.

The inner or free end of the arm is turned 50 at an angle, as shown at 40, and provided with a coiled hook 41 adapted to receive a pulley 42. The form of the hook 41 is such that it is practically impossible for the pulley to become detached therefrom in any 55 position of the arm.

As shown in Fig. 1, when the device is to be used, the arm 29 will be swung inwardly and upwardly to the desired elevation within the building, and then the nut 32 60 will be tightened causing the boss 33 to grip into the front end of the sleeve 30, thereby gripping the arm at the points 34 and 35 into one pair of notches of the flange 13 of the bracket. This action locks the arm 65 in rigid position and the clothes line will

then operate freely between the pulleys 42 and 43, making it convenient for the operator to hang the clothes directly upon the line without reaching out or through the window, the line being projected step by 70 step while the clothes are being connected thereto in the usual manner. After the wash has been hung out, both runs of the line are lifted and supported upon the outer end of the sleeve 30 or between the arm and 75 the flange of the nut 32, whereby the normal tension upon the line is preserved. Upon loosening the nut 32 the arm is then allowed to swing downwardly as shown in Fig. 2, 80 permitting the window to be closed. The nut may then be either tightened or not, as may be desired, the strain upon the line being borne as before upon the pulleys and over the pivot pin 27. The arm 29, however, is sufficiently stiff or strong to prevent 85 bending or buckling thereof. When the clothes line is empty, it may assume the position shown in dotted lines in Fig. 2, being thereby perfectly loose to provide ample movement for the pulley 42 and free end of 90 the arm. We provide notches 44 in the upper and lower portions of the flange 13 in which to grip the arm, if desired, when the device is idle.

We claim:—

1. In a clothes line support, the combination of a bracket, means to secure the bracket rigidly to the side of a window frame, the bracket comprising a web having a central boss and a peripheral flange, a sleeve fitted 100 at one end upon the boss, a line supporting arm fitted diametrically through the middle portion of the sleeve and bearing upon the flange at points diametrically opposite from the axis of the boss, and means acting upon the other end of the sleeve to lock the arm and sleeve upon the bracket.

2. In a clothes line support, the combination of a stationary bracket comprising a boss and bearing points diametrically opposite the same, a pivot pin fitted axially through said boss, a line supporting arm co-operating with said bracket at said bearing points, and means coöperating with the arm and pivot pin to grip the arm in fixed position upon the bracket.

3. In a clothes line support, the combination of a bracket, means to secure the bracket in rigid position, said bracket including a web having a rigid boss and peripheral bearing points, a short cylindrical sleeve fitted at one end upon said boss, a line supporting arm secured to the sleeve and adapted to coöperate with certain of said bearing points, a pivot pin arranged 120 co-axially with said boss, and a clamping nut coöperating with the other end of the sleeve and with said pivot pin, substantially as set forth.

4. In a clothes line support, the combina- 130

tion of a rigid bracket comprising a disk-like web having a central hole and a notched peripheral flange surrounding the hole, the notches being arranged in pairs, each pair being diametrically opposite from the axis of the hole, a pivot pin fitted in said hole, a line supporting arm mounted to swing around the pin and adapted also to coöperate with any one of said pairs of notches, and means coöoperating with the arm and said pin to lock the arm in fixed position.

5. In a clothes line support, the combination of a rigid bracket having a central rigid boss and a flange surrounding the boss parallel thereto, a pivot pin fitted axially through the boss, a line supporting arm

adapted to coöperate with said flange, a short cylindrical sleeve fitted at one end upon said boss and connected to the arm, the arm having a hole through which the pivot 20 pin projects at the axial center of the sleeve, and a nut secured to the free end of the pivot pin and coöperating with the other end of the sleeve to lock the arm in fixed position, said nut and sleeve serving also as 25 a support for the intermediate portion of the clothes line, substantially as set forth.
